DESIGN FOR A RADIO SET

Howard J. Tyzzer, Cincinnati, Ohio, assignor to
The Crosley Radio Corporation, Cincinnati,
Ohio, a corporation of Ohio

Application August 2, 1938, Serial No. 79,038

Term of patent 14 years

To all whom it may concern:

Be it known that I, Howard J. Tyzzer, a citizen of the United States and a resident of Cincinnati, in the county of Hamilton and State of Ohio, have invented a new, original, and ornamental Design for a Radio Set, of which the following is a specification, reference being had to the accompanying drawing, forming part thereof.

In the drawing:

Figure 1 is a right hand end elevational view of my radio set in one position of use.

Figure 2 is a left hand end elevational view of my radio set in another position of use.

Figure 3 is a top plan view of my radio set when in the position shown in Figure 1.

Figure 4 is a front elevational view of the set in the same position.

Figure 5 is a bottom view of the set in the same position.

Figure 6 is a bottom view of the set in the position shown in Figure 2.

I claim:

The ornamental design for a radio set, as shown.

HOWARD J. TYZZER.

CERTIFICATE OF CORRECTION.

Design No. 113,924.

March 21, 1939.

HOWARD J. TYZZER.

It is hereby certified that the name of the assignee in the above numbered patent was erroneously described and specified as "The Crosley Radio Corporation" whereas said name should have been described and specified as The Crosley Corporation, of Cincinnati, Ohio, a corporation of Ohio, as shown by the record of assignments in this office; and that the said Letters Patent should be read with this correction therein that the same may conform to the record of the case in the Patent Office.

Signed and sealed this 9th day of May, A. D. 1939.
